WILLIAM B. HOPWOOD, OF BEACON FALLS, AND HENRY S. MARLOR, OF NAUGATUCK, CONNECTICUT, ASSIGNORS TO THE GOODYEAR'S INDIA RUBBER GLOVE MANUFACTURING COMPANY, OF NAUGATUCK, CONNECTICUT, A CORPORATION OF CONNECTICUT

DESIGN FOR A COMBINED SOLE AND HEEL

Application filed November 13, 1931. Serial No. 41,722. Term of patent 7 years.

To all whom it may concern:

Be it known that we, WILLIAM B. HOPWOOD and HENRY S. MARLOR, both citizens of the United States, residing at Beacon Falls and Naugatuck, respectively, in the county of New Haven and State of Connecticut, have invented a new, original, and ornamental Design for a Combined Sole and Heel, of which the following is a specification, reference being had to the accompanying drawings, forming part thereof, in which:

Figure 1 is a plan view of a combined sole and heel, showing my new design, and

Figure 2 is a sectional elevation taken on line 2—2 of Fig. 1.

We claim:

The ornamental design for a combined sole and heel, as shown.

Signed at Beacon Falls, in the county of New Haven, and State of Connecticut, this 10th day of November, 1931.

WILLIAM B. HOPWOOD.

Signed at Naugatuck, in the county of New Haven, and State of Connecticut, this 10th day of November, 1931.

HENRY S. MARLOR.
